DESIGN FOR A KNITTED DRESS

Joseph Guttman, New York, N. Y.

Application August 22, 1935, Serial No. 58,243

Term of patent 3½ years

To all whom it may concern:

Be it known that I, Joseph Guttman, a citizen of the United States of America, residing in Manhattan, county of New York, and State of New York, have invented a new, original, and ornamental Design for a Knitted Dress, of which the following is a specification, reference being had to the accompanying drawing, forming part thereof, wherein,

The tab collars, which extend around the front of the neckline, have a knitted tie extending around the back portion of the neckline, which tie is pulled through underneath the tab collar, tying at front.

I claim:

The ornamental design for a knitted dress, substantially as shown, and described.

JOSEPH GUTTMAN.
